TABLE

Evalin S. Gilbert, 2121 North Bay Shore Drive,
Miami, Fla. 33137

Filed Nov. 20, 1972, Ser. No. 308,041

Term of patent 14 years

Int. Cl. D6—03

U.S. Cl. D6—177

FIG. 1 is a perspective view showing a table incorporating one embodiment of my new design; and

FIG. 2 is a perspective view showing a table incorporating a second embodiment of my new design.

The side and end of the table not shown are mirror images of the side and end shown, respectively.

I claim:

The ornamental design for a table, substantially as shown and described.
